UNITED STATES PATENT OFFICE.

WALTER ELLMAN, OF LONG ISLAND, NEW YORK.

MUSIC-LEAF TURNER.

1,131,125.

Specification of Letters Patent.

Patented Mar. 9, 1915.

Application filed August 21, 1914. Serial No. 857,913.

To all whom it may concern:

Be it known that I, WALTER ELLMAN, a subject of the Czar of Russia, residing at Long Island, in the county of Queens and State of New York, have invented certain new and useful Improvements in Music-Leaf Turners; and I do hereby declare the following to be a full, clear, and exact description of the invention, such as will enable others skilled in the art to which it app pertains to make and use the same.

The primary object of this invention is the provision of a music leaf turner which shall be simple, conveniently portable and capable of being operatively positioned upon practically any construction or type of musical instrument or music stand.

Another object is the provision of a device of this character embodying means whereby the pages of a musical composition may be successively turned during the rendition thereof.

With these and other objects in view, the invention consists in the novel construction, arrangement and formation of parts as will be hereinafter specifically described, claimed and illustrated in the accompanying drawings, in which:

Figure 1 represents a front elevation of the music stand, showing the application thereto of the improved music leaf turner. Fig. 2 represents an enlarged side elevation of the music leaf turner. Fig. 3 represents a sectional view on the line 3—3 of Fig. 2. Fig. 4 represents a fragmental sectional detail view through the frame structure of the turner, and Fig. 5 represents a side elevation of the music leaf turner as applied to a piano or similar musical instrument. Fig. 6 represents a fragmental top plan view of the leaf turner.

Referring to the drawing in detail, wherein similar reference numerals designate corresponding parts throughout the several views, the numeral 7 indicates the body or frame structure of the music leaf turner including front and rear walls 8 and 8^a respectively, which are preferably removably secured to the longitudinal edges of the base plate 7 by screws 9^a or equivalent means. A shaft 9 is rotatably mounted adjacent one end of the frame structure and projects laterally of the front wall 8, as clearly illustrated in Fig. 2. The front wall 8 is enlarged, as indicated at 10, at the point where the shaft 9 projects therethrough and

a set screw 11 is fitted into the enlargement 10 for locking the shaft 9 against rotation. A plurality of arms 12 are formed with enlarged inner ends 13 pivotally mounted upon the shaft 9. The enlarged ends 13 of the arms are formed with recesses in which are mounted spiral springs 14 secured at one end to the shaft 9 and at the opposite end to the enlarged ends 13 of the arms for normally tending to rotate said arms in the direction of the arrow in Fig. 3. The enlarged ends 13 of the arms are further provided with teeth 15.

A plurality of locking members 17 are pivotally mounted on a shaft 18 secured through the front and rear walls 8 and 8^a of the frame structure. The locking members 17 are provided with angular ends 19 adapted to interlock with teeth 15 to lock the arms 12 against swinging movement on the shaft 9 under the influence of the springs 14. A disk 24 is mounted for longitudinal sliding movement on a shaft 25 rotatably mounted in the front and rear walls 8 and 8^a of the frame structure and are preferably rectangular in cross section and fitted within a similarly shaped aperture in the disk 24 to prevent rotation of the latter. A pair of oppositely directed pins 26 project laterally from the side faces of the disk 24 and are adapted, when said disk is rotated, to engage the free ends of the locking members 17 to release the pivoted arms 12. The disk 24 is normally retained against the rear face of the front wall 8 of the frame structure by the tension of a spring 27 coiled about the shaft 25 and engaged at its opposite terminals against the disk and the rear wall 8^a. A shaft 28 is mounted for longitudinal sliding movement through the frame structure and is normally retained in forwardly extended position by the tension of a spring 29 engaged at its opposite extremities against a button 30 formed at the forward extremity of said shaft and the front face of the front wall 8 of the frame structure. A collar 31 is rigidly secured to the shaft 28 between the front and rear walls 8 and 8^a of the frame and is adapted to engage the disk 24 to move the latter to initial position when the shaft 28 is moved rearwardly.

As illustrated in Figs. 1 and 2 the music leaf turner may be attached to the standard 32 of a music stand by a bracket designated generally by the numeral 33 and including

a longitudinally slotted bar 34 having a recess in one end adapted to receive the standard 32 and carrying at its opposite end a plate 35 secured to the base plate 7 and adjustably secured to the bar 34 by a bolt 36. A set screw 37 is fitted in the recessed end of the bar 34 and is adapted to engage the standard 32 of the music stand to lock the bracket in adjusted position thereon. A guide 38 is secured to the front plate 8 of the frame structure and is formed with an aperture slidably receiving the vertically disposed bar 39 having the lower end 40 directed outwardly to provide a finger grip and secured at its upper terminal to a lever 41 rigidly secured to the shaft 25 and also connected with the frame structure by a spring 43 normally tending to rock said lever to raise the operating bar 39.

While I have here shown only two turner arms 12 it will be understood that as many arms as needed may be utilized without greatly increasing the size and weight of the turner.

In use, the shaft 28 is moved inwardly carrying therewith the disk 24. The arms 12 are turned to the right, to the position illustrated in full lines in Fig. 3, and when locked by the engagement of the angular ends 19 of the locking members 17 with the teeth 15 of the enlarged ends of said arms, in locked position, the ends 21 of the locking members are disposed in the path of the disk 24 and prevent the latter from returning to its forward position under the influence of the spring 27. The free extremities of the arms 12 are subsequently engaged behind the pages 45 of the musical composition. To turn the page, the operating bar 39 is depressed, swinging the lever 41 and rocking the shaft 25 to which said lever is keyed. The disk 24 is rotated with the shaft 25 and the pins 26 of said disk engage and depress the free terminal of the locking member 17 simultaneously raising the angular ends 19 thereof and releasing the rearmost arm 12 and permitting it to move leftward under the influence of the coil spring 14. The arm 12 carries with it the page 45 of music behind which it is engaged, and the end 21 of the locking member 17 associated with said rearmost arm 12 is moved upwardly, after operation of said arm, by the tension of the spring 20. As the end 21 of said locking member is moved upwardly it is disengaged from the disk 24 which is permitted to move forwardly under the influence of the spring 27 and engage the free end 21 of the locking member associated with the arm 12. In this position, the disk 24 and pins 26 release the next arm 12 when the operating bar 39 is again actuated, the disk 24 continuing to move forwardly at each operation of the bar 39 until each of the arms 12 is released. When desired, an angular securing bracket 46 may be substituted for the bracket 33 for securing the music leaf turner to pianos and similar musical instruments. Further, if desired, the operating bar 39 may be connected with a pedal 46' by a rod 47 for operating the music leaf turner by foot.

What I claim is:

1. A music leaf turner comprising a frame structure, a plurality of arms pivotally mounted in said frame structure, means normally tending to swing said pivoted arms, a plurality of locking members pivotally mounted in said frame structure for locking said pivoted arms against swinging movement, a shaft rotatably mounted in said frame structure, a disk non-rotatably mounted on said shaft and movable successively against said locking members, means normally tending to move said disk forwardly on said shaft into engagement with said locking members, and means on said disk for engaging and releasing said locking members.

2. A music leaf turner comprising a frame structure, a plurality of arms pivotally mounted in said frame structure, means normally tending to swing said pivoted arms, a plurality of locking members pivotally mounted in said frame structure, means normally tending to move said disk into engagement with the free ends of said locking members, said locking members being adapted, when released, to swing out of the path of said disk to permit the latter to move forwardly under the influence of the spring into engagement with the next locking member, and means on said disk adapted to engage and release said locking members.

In testimony whereof I affix my signature in presence of two witnesses.

WALTER ELLMAN.

Witnesses:
